ESCAPEMENT MECHANISM

Peter F. Gattuso, Chicago, Ill., assignor to Woodstock Typewriter Company, Woodstock, Ill., a corporation of Illinois

Application May 1, 1940, Serial No. 332,787

1 Claim. (Cl. 197—88)

This invention relates to typewriters in general and particularly to escapement mechanism therefor.

The primary object of the present invention is the provision of new and improved means, constructed and arranged in a predetermined manner to absorb the impact and jar occurring during the operation of the typewriter and thereby resiliently bring a movable member to rest quickly but gently without excessive vibration or rebound.

Another object of the invention resides in the provision of an improved shock absorbing element in the form of a resilient shelf against which a movable part of the typewriter escapement mechanism has abutting or contacting engagement to bring the parts to resting position at the conclusion of its movement and thereby overcome jars, noises, vibration and clashing of parts.

A more specific object of the invention is the provision of a bracket member, made of flexible, resilient spring steel positioned adjacent an arm of a bell-crank part of typewriter escapement mechanism so that as an operating end of the bell-crank approaches the end of its travel toward a limiting stop, the bracket will be engaged and cushion the blow, thereby preventing a direct hard blow against the stop and causing the part to come to rest silently and softly without hindering the speed or operativeness of the said part.

Numerous other objects and advantages will be apparent throughout the progress of the following specification.

The accompanying drawing illustrates a selected embodiment of the present invention and the views therein are as follows:

Fig. 1 is a detail rear elevational view of escapement mechanism applied to a typewriter and embodying the invention, the parts being shown in normal or rest position;

Fig. 2 is a view similar to Fig. 1 but showing the parts in an advanced position;

Fig. 3 is a detail perspective view of some of the escapement mechanism and embodying the invention; and

Fig. 4 is a detail perspective view of the shelf employed as the resilient stop member.

The particular mechanism herein shown to illustrate the invention is shown applied to the popular, well known "Woodstock" typewriter although the invention is susceptible for application to other makes of typewriters. The "Woodstock" typewriter herein illustrated in part com-

prises a typewriter frame 5, which is provided with rails upon which a carriage (not shown) is free to slide transversely.

A rack 6, having the usual limited pivotal movement, and spring urged in a predetermined normal operating position, is mounted on the carriage at the rear of the machine and moves transversely with the carriage. The carriage with its attached rack 6 is drawn toward the right, Fig. 1, by suitable resilient means, such as by a tape fastened to a part of the carriage and to a revolubly mounted spring urged casting mounted on the typewriter frame. This resilient means is permitted to draw the carriage to the right, Fig. 1, only when the escapement mechanism is released by the depression of a key or the spacing bar, but the action tending normally to draw the carriage to the right is constant.

20 The resilient means tends to urge the carriage in a predetermined position, but the action of this resilient means on the carriage is retained or resisted by the rack 6 which is normally in engagement with a pinion 7 rotatably mounted about a pivot pin 8. The pinion 7 is free to rotate in a counter-clockwise direction, as viewed in Figs. 1 and 2, but is held rigidly from movement in a clockwise direction by a pawl 9 normally maintained in engagement with the pinion. 25 The pawl 9 is pivotally mounted at 10 on an escapement wheel 11 which is mounted operatively on the pivot pin 8, being arranged adjacent the pinion 7 for proper co-operation therewith. A spring 12 on the escapement wheel 11 has engagement with the pawl 9 to hold the pawl in engagement with the pinion 7. The pawl 9 is arranged so as to permit movement freely of the pinion 7 in a counter-clockwise direction, as viewed in Figs. 1 and 2, so that the carriage may be returned readily in the usual manner against the action of the aforementioned resilient means.

40 The escapement wheel 11 is provided with a plurality of outwardly extending peripheral teeth 13, equal to the number of teeth 14 on the pinion 7. In actual practice it has been found that sixteen teeth on the escapement wheel and pinion are very satisfactory to the proper performance and operation of the machine. The escapement wheel 11 may include an integral sleeve formed therewith and arranged about the pivot pin 8, and the pinion 7 may be rotatively mounted on this sleeve. The escapement wheel 11 and the pinion 7 may be retained in assembled relationship by a set screw threadedly en-

gaging the pivot pin 8, and the pivot pin 8 may be operatively supported in a bore provided in the machine frame in a manner well known in the art.

The remainder of the escapement mechanism is of well known construction and includes a supporting bracket member 15 which is supported at 16 and 17 between pivot bearings 18 and 19 threadedly mounted in opposed rigid projections 20 and 21 on the machine frame 5. A space link 10 operated by the spacing bar may be operatively connected to a part 22 on the bracket 15 to tilt the supporting bracket 15 from front to rear so as to disengage a movable stop dog 23 from a tooth 13 on the escapement wheel. Immediately 15 upon movement of the dog 23 from a tooth 13, the resilient means pulls the carriage until the freed tooth 13 engages the fixed dog 24. Upon release of the spacing bar, the bracket 15 will return to its normal position whereby the tooth 13 will be freed from the fixed dog 24, and the next 20 succeeding tooth 13 will be at rest against the movable dog 23. The tilting or pivotal movement of bracket 15 is also accomplished by the depression of a key; the key having an operative connection with a frame 25 pivoted on pins 26, and having a part engageable with the bracket 15 to tilt the bracket and permit the escapement 25 which is referred to above.

The dog 23 comprises a bell-crank 27 which is pivoted at 28 to the bracket 15. An arm of the bell-crank, which is the movable dog 23, is engageable with the teeth 13 on the escapement wheel 11. The other arm 29 of the bell-crank 27 has a spring 30 fastened thereto, tending to urge the bell-crank about its pivot 28 toward a fixed stop pin 33. The bell-crank 27 has a striking face or stop abutment 32 adapted for engagement with another stop pin 31. The bell-crank 27 has its upper arm (the dog 23) positioned between the stop pin 31 and the stop pin 33, whereby the lateral movement of dog 23 is limited.

The fixed dog 24 is fastened to the bracket 15 by a fastening member 34, the stem of which passes through a slot 35 in the bracket 15 to permit adjustment of the fixed dog 24.

The striking of the teeth 13 on the escapement wheel 11, against the dog 23, shifts the dog 23 on its pivot to the left, Figs. 1 and 2, causing the face 32 to move toward the stop pin 31. The direct contact of the face 32 against the pin 31 would set up a vibration as well as a clashing sound or noise each time a key or the space bar was released after being first depressed. To overcome these disadvantages, resilient means is provided to retard the movement of the dog 23 just prior to the time the striking face hits against

the stop pin 31. This resilient means comprises a bracket or angle member 36, Fig. 4, made of stiff spring steel and having its upper leg or arm 37 fixed to the bracket 15 and its lateral leg 38 extending outwardly, as viewed in Figs. 1 and 2, so as to be engaged by the arm 29 of the bell-crank 27 during its pivotal movement to the left, Figs. 1 and 2. The shelf presented by the leg 38 therefore cushions the blow of the bell-crank 27 before the face 32 strikes the stop pin 31. The cushioning of the dog therefore reduces vibrations to a minimum, and overcomes any noises which would be caused by the clashing and direct striking of rigid parts.

The invention therefore provides a new and novel arrangement of parts to overcome and reduce noises and vibrations to a minimum. The cushioning element 36, while relatively small and appearing insignificant provides just the proper amount of cushioning necessary because of its particular location, construction and the kind of material from which it is made. The element may be applied to existing typewriters as well as to new constructions. The parts are constructed and arranged to perform the proper function at precisely the proper time; moreover, it has been found in actual practice that wear on the parts is lessened, and because of the elimination of shock and jar the typewriter does not become noisy after extended use. Furthermore, the strain on the operator is lessened because noise is reduced and considerable vibration is eliminated.

Changes may be made in the form, construction and arrangement of the parts without departing from the spirit of the invention or sacrificing any of its advantages and the right is hereby reserved to make all such changes as fairly fall within the scope of the following claim.

The invention is hereby claimed as follows:

Escapement mechanism for typewriters comprising a pivotally mounted bracket, a bell-crank pivotally mounted on the bracket, means to move the bell-crank, stop means on the bracket on each side of the bell-crank to limit the movement thereof, one part of the bell-crank adapted for engagement with teeth on an escapement wheel to hold the wheel, and an angle bracket of L-shape and formed of spring metal fixed to the bracket by one leg and having its other leg freely projecting outwardly therefrom into the path of movement of one arm of said bell-crank to form a shelf against which said arm of the bell-crank engages as the bell-crank moves toward one of said stop means to cushion the bell-crank movement and prevent the bell-crank from striking the stop means a hard blow.

PETER F. GATTUSO.
